Inventor:

George Goebel,

By Spear, Middleton, Donaldson, Haag
Atty's.

UNITED STATES PATENT OFFICE.

GEORGE GOEBEL, OF CATONSVILLE, MARYLAND.

GAS IGNITER.

Application filed September 26, 1923. Serial No. 664,907.

To all whom it may concern:

Be it known that I, GEORGE GOEBEL, a citizen of the United States, and resident of Catonsville, in the county of Baltimore and 5 State of Maryland, have invented certain new and useful Improvements in Gas Igniters, of which the following is a specification.

My invention relates to a safety device 10 for incorporation with gas burners, and is intended to eliminate the use of matches, or the like, in igniting the gas, and also to reduce explosion hazards to a minimum due to escaping gas.

15 The invention consists essentially in providing an air burning medium in proximity to a jet of the combustible mixture supplied to the burner, through which sparking device passes a constant electric current the 20 circuit for which is automatically closed as long as the flow of combustible gas continues.

I have illustrated one form of device in the drawings, which is a preferred embodiment of the invention, although I do not 25 wish to be specifically limited thereto.

In these drawings:—

Figure 1 is a plan view of the device and the electric circuit.

30 Fig. 1^a is a detail of the make and break device.

Fig. 2 is a view of the igniter hood with a section of burner.

Fig. 3 shows a plug applied to a torch 35 type of burner.

Fig. 4 is a detail of the gas cock.

Referring with particularity to these drawings, I have shown a gas main at 1 connected to an electric mixer 2 for determining the proper mixture of gas and air 40 which will be supplied to the burner 3. This burner may take either the form of the usual pipe having perforations therein, which results in a series of individual flames, or it 45 may take the form of the torch burner 4 having but a single flame 5.

In the gas main 1 I provide an ordinary stop cock 6 to the top of which is secured a handle element 7 to open and close the same 50 in the usual manner, but so arranged that it lies athwart the gas main when the flow of gas is cut off.

Mounted upon the burner 3 I provide a hood 8 which terminates in a band 9 looped 55 about the burner 3 in a manner to meet itself, and secured to the burner 3 as by means

of bolt 10. It is desirable that the hood 8 extend over the burner so as to catch an amount of gas supplied to the burner. A spark plug 13, or other suitable igniting device, is secured to the band 9 at a point beneath the hood and above the burner so that the gas escaping from the burner will be caught by the hood, which will be in proximity to the sparking points, and ignited from this point.

The electric circuit for the sparking plug 13 is arranged as follows: The shell of the spark plug 13 is grounded through the hood and its band to the gas conduit pipe 1 in 70 the usual manner. The other insulated electrode of the spark plug has connected thereto a lead 14, which, with the lead 12 also grounded on the pipe 1, forms a secondary, or high tension, circuit. A lead 15, 75 suitably connected to a source of energy, as the ordinary lighting circuit of 110 or 220 volts, forms with the lead 16, the primary circuit. An induction coil, or transformer, may be interposed between the primary and 80 secondary circuits to deliver the proper amount and type of current to the spark plug 13.

In order to insure current reaching the terminals of the spark plug 13 whenever gas 85 is flowing through the burners, I provide a circuit closer which consists of a base 22 upon which is mounted a lever 17 pivoted as at 18. One end of the lever 17 is provided with a roller 19 which is suitably insulated 90 from the rest of the device. The other end of the lever 17 is provided with a contact member 20 which may be made to contact with the binding post 21 to which is secured the lead wire 16. The contact 20, when brought 95 in proximity with the contact 21, closes the primary circuit which induces a current in the secondary circuit and a spark between the terminals of the spark plug. A coil spring 23, seated in a well 24 in the base 22, 100 exerts tension on the under side of the roller end of the lever 17, pressing it in an outwardly position. The handle 7 on the cock 6 is so arranged in relation to the circuit breaker that when the handle occupies the 105 shut-off position, the end thereof engages the roller 19 which causes a depression in that end of the lever 17 with the result that the contacts 20 and 21 are separated and the circuit broken.

Upon reversing this operation, or when the cock is turned to the on position, as in lighting the burners, the cir- 110

cuit is automatically closed because the handle 7 clears the roller 19, thus allowing the spring 23 to press together the contacts 20 and 21. The circuit is now complete and 5 the spark will occur at the terminals of the spark plug 13. A spark will continue at this point as long as current flows through the circuit.

It will thus be apparent that the burner 10 will automatically light as soon as the gas is turned on, even to a slight extent, as it is merely a matter of adjustment to have the roller 19 clear the handle 7 to make contact between members 20 and 21 at either wide 15 open or slightly open position of the cup. It will also be noted that should the flow of gas temporarily cease, or the flames be blown out, the gas will instantly be ignited upon resuming the flow without thought from 20 outside help, being entirely automatic.

Having thus described my invention, what I claim is:—

1. In combination, a gas burner, a pipe 25 supplying fuel thereto, a cock in said pipe, a handle therefor, a hood mounted upon said burner and adapted to receive a portion of the gas escaping from said burner, igniting means within said hood, an electric circuit therefor, a circuit maker and breaker in said

circuit, including a pivoted lever, said cock 30 handle, when in the shut-off position, causing a depression of said lever whereby the circuit is interrupted.

2. In combination, a gas burner, a pipe 35 supplying fuel thereto, a band encircling said pipe, said band having an upwardly extending portion terminating in an overhanging hood, an outlet in said pipe for fuel, said hood overlying said outlet, and ignition means between the fuel outlet and 40 the hood.

3. In combination, a gas burner, a pipe 45 supplying fuel thereto, means to ignite the fuel escaping from said burner, including an electric circuit, said circuit comprising a pivoted lever making electrical contact between two points and normally closing the circuit between said points under action of the spring, a cock in said fuel supplying pipe, a handle therefor which in shut-off 50 position extends outwardly from said pipe, a roller on the end of said pivoted lever, the edge of the handle engaging the roller when the cock is in the shut-off position, which breaks the electric circuit. 55

In testimony whereof, I affix my signature.

GEORGE GOEBEL.
